Claims priority, application Germany, Aug. 16, 1962, D 39,630

11 Claims. (Cl. 94—48)

The present invention relates to vibrating and tamping devices used for compacting masses such as earth used for building foundations, roadways, said, concrete, etc.

Conventional devices of this type have rotary, unbalanced weights which due to their centrifugal force cause the devices to rise up from the mass and to fall back down on the same and also these forces have horizontal components which cause the device to advance itself with respect to the mass which is being worked on. Devices of this type, however, have such complex vibration systems that it is impossible to calculate in advance the exact manner of operation of the device in actual practice, so that as a result the behavior of the device in actual practice is to an undesirable extent unpredictable. Furthermore, it frequently happens that the known devices rise so high into the air during one revolution of the rotary unbalanced weights thereof that these weights continue on the next revolution and change the direction of movement of the device before the latter engages the mass which is to be compacted, so that the energy which should be applied to the mass which is being worked on is instead simply applied to the free air.

There are also certain known tamping devices which have tamping weights which alternately engage the mass which is worked on one of the weights rising while the other engages the mass and vice versa, but the difficulty with these devices is that when they encounter the irregular surface of roadways, sand piles, etc., these devices very frequently get hung up on one of the weights while the other weight simply turns in the free air and thus the device cannot continue to operate unless it is dislodged. Also, the tamping force provided from such devices are not very great and are not always distributed in the most desirable manner. In addition, it is not possible to obtain with devices of this type more than 120 beats per minute, so that a suitable vibration cannot be obtained. For this purpose it should be possible to provide a beat rate on the order of 1000–3000 beats per minute.

Of course, there are known devices which have hydraulically or pneumatically operated pistons for adjusting the vertical and horizontal movements of the vibrating device, but devices of this type are extremely complex and expensive.

It is accordingly a primary object of the present invention to provide a vibrating and tamping device which avoids all of the above drawbacks. Thus, the objects of the invention include the provision of a device of relatively simple and inexpensive construction which will be able to operate with a relatively high number of beats per minute while at the same time reliably making contact with the mass which is worked on once during each revolution of the crank shafts of the device.

Furthermore, it is an object of the invention to provide a device which can be used for vibrating purposes and which can then be used for tamping purposes simply by changing the speed of rotation of the crank means of the device.

It is furthermore an object of the invention to provide a device of the above type which requires no spring-cushioned vibratory masses so that it is relatively simple to calculate in advance the behavior of the device of the invention and in addition its construction is considerably simplified.

2

In fact, it is an object of the invention to provide a device of the above type wherein all of the moving parts are coupled together in such a way that they are all compelled to move with respect to each other in a predetermined manner.

It is furthermore an object of the present invention to provide a device of the above type which will automatically adapt itself to the nature of the mass which is being worked on so that its manner of operation will automatically respond to the nature of the material in such a way that materials which are already in a highly compacted condition will not be compacted much more while loosely compacted masses will be worked on to a greater extent in a fully automatic manner by the device of the invention.

It is also an object of the present invention to provide a device of the above type which will move along the material which is being worked on at a uniform rate, in contrast to known structures where the known device stops and starts its movement with respect to the mass which is being worked on, and furthermore the objects of the present invention include the provision of a device of the above type which will move relatively quickly along a mass which is highly compacted and more slowly, in a fully automatic manner, upon masses which are loosely compacted, so that in automatic response to the nature of the material which is worked on the device of the invention will provide the best possible treatment.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a partly schematic, partly sectional side view of one possible construction of a vibrating and tamping device according to the present invention;

FIG. 2 is a transverse sectional view taken along line 2—2 of FIG. 1 in the direction of the arrows but omitting the driving engine which is located at the upper part of the plane in which the section of FIG. 2 is taken; and

FIG. 3 is a diagrammatic illustration of the manner in which the structure of the invention operates.

The entire assembly which forms the device of the invention includes essentially only three moving weights or masses. One of these moving weights or masses is formed by the working plate means 2 which has the form of an open-top container, this working plate means 2 having a bottom wall which engages the mass which is to be compacted and having a continuous side wall extending upwardly from the periphery of the bottom wall. The continuous side wall of the working plate means 2 has a pair of opposed parallel side wall portions which respectively receive crank pins of a pair of crank means 50 of the invention. Thus, the structure includes a pair of crank means 4a and 4b, and the crank means 4a has a pair of outer coaxial crank pins 41a which are respectively received in mating openings in the pair of opposed parallel side wall portions of the working plate means 2, while the other crank means 4b, which is identical with the crank means 4a, has a pair of outer coaxial crank pins 41b which are respectively received in mating openings in the opposed parallel side wall portions of the working plate means 2. It will be noted that the working plate means 2 is located at the lowest part of the apparatus and has a continuous bottom wall which forms the only part of the apparatus which engages the mass which is to be compacted. Each crank means 4a and 4b includes a pair of spaced coaxial discs 42a, 42b respectively, rotatably mounted in openings formed in a pair of op-

posed parallel side walls of a first support means 1, a pair of outer or first laterally projecting offset crank pins 41a, 41b, respectively, and a body portion, namely, a second or inner crank pin 43a, 43b, respectively, connecting each pair of discs. The axis "a" of the outer or "first" crank pins is offset a distance r^2 from the axis of rotation "b" of the crank discs which constitutes also the axis of rotation of the respective crank means. The body portion or inner crank pin of the crank means is 180° opposed to said outer crank pins and spaced a distance r^3 on the opposite side of the axis of rotation "b" of said crank discs. Thus, crank means 4a includes a pair of coaxial crank discs 42a which have their common axis coinciding with the axis of rotation of the crank means 4a, and the pair of outer or first crank pins 41a respectively have their common axis located at a distance r^2 from the common axis of the crank discs 42a. In the same way, the crank means 4b which is identical with the crank means 4a has a pair of coaxial crank discs 42b which have a common axis "b" forming the central axis of rotation of the crank means 4b, and the common axis "a" of the pair of outer or first crank pins 41b are also spaced from the common axis "b" of the crank discs 42b by the distance r^2 , as is shown most clearly in FIG. 2. These crank discs 42a and 42b are respectively supported for rotary movement in mating openings formed in a pair of opposed parallel side walls of an elongated channel member 1 which has a top wall from opposite sides of which the side wall of the channel member extend downwardly, so that the cross section of the channel member 1 has the configuration of an inverted U, and this channel member 1 forms a first support means for the structure of the invention, this first support means forming the second of the three principal masses of the vibrating and tamping devices of the invention. It will be noted that the channel member or first support means 1 extends downwardly into and is received within the elongated open-top container which forms the working plate means 2 and which latter constitutes second support means for supporting said first support means.

The pair of crank discs 42a are interconnected by way of an inner or second crank pin 43a which extends between and is fixed at its ends to the pair of crank discs 42a, and in the same way the pair of crank discs 42b are fixed to each other by a crank pin 43b identical with the crank pin 43a and extending between and fixed to the pair of discs 42b, shown most clearly in FIGS. 1 and 2, and each of the pins 43a and 43b constituting a second crank pin and having with respect to the axis "b" of its crank means an axis "c" which is spaced therefrom by a distance r^3 (FIG. 2), and furthermore the arrangement is such that for each crank means the axis of the crank pin 43a or 43b is displaced with respect to the common axis of the outer crank pins 41a or 41b by an angular distance 180° with respect to the axis of the crank means. The third principal mass of the device of the invention is formed by a balancing plate means 3 in the form of an elongated block of metal, for example, which is formed with a pair of parallel bores in the region of the respective ends thereof and through which the crank pins 43a and 43b respectively extend with a snug sliding fit. It will be noted that the balancing plate means 3 is situated in the space enclosed within the channel member or support means 1.

The pair of crank discs 42a and 42b which are supported for rotation by one of the walls of the channel member or first support means 1 (the left wall as viewed in FIG. 2) respectively fixedly carry a pair of ring gears 5a and 5b which are fixed coaxially to these crank discs, and these ring gears 5a and 5b mesh with an intermediate gear 6 which is supported for rotation by the same side wall of the channel member 1, so that in this way the several gears form a transmission means which is also accommodated in the space within the channel member 1 and which interconnects the pair of crank means in such a way that they are compelled to rotate in synchronism. 70

It will be seen, however, that in any event the balancing plate means 3 because of its connection to the pair of crank pins 43a and 43b compells the pair of crank means 4a and 4b to rotate in synchronism. Thus, it will be seen 5 that the structure includes a pair of crank means 4a and 4b which are identical and which have at any given instant the same positions relative to the first support means 1, so that the pair of crank pins 41a and 41b at one side of the assembly will at any given instant have the same positions relative to the axes of the pair of crank means while the pair of crank pins 43a and 43b will also have at any given instant the same relative positions with respect to the axes of the pair of crank means, but the positions of the axes of the crank pins 43a and 43b will 15 always be displaced by 180° with respect to the positions of the crank pins 41a and 41b. These latter pins are connected to the working plate means while the crank pins 43a and 43b are connected to the balancing plate means 3, and of course the entire structure is supported by the second support means 2.

In order to drive the structure the first support means 1 carries at its upper surface a driving motor in the form of an internal combustion engine 8, in the illustrated example, and this motor or engine 8 is supported by way of springs 13 on a plate which is in turn separated by 25 additional springs 13 from the member 1, so that in this way the driving motor 8 is insulated from the remainder of the structure in such a way that the motor 8 is protected against shocks. A transmission shaft 9 is connected through universal joints on the one hand to the output or drive shaft of the drive motor 8 and on the other hand to the input of a reversible transmission assembly 7 the output gear 10 of which meshes with the ring gear 5a which of course has its rotation transmitted through the gear 6 to the other ring gear 5b. It is 30 pointed out that this arrangement is illustrated only by way of example and the output gear of the transmission could just as well mesh with the ring gear 5b or indeed the intermediate gear 6.

One end of the support means 1 is provided with a pair of eyes 11 carrying a pivot pin on which one end of a guiding pole 12 is supported, and the operator by 40 engaging the pole 12 can guide the direction in which the device of the invention moves.

During operation of the device the working plate means 2 is compelled to move with the outer crank pins 41a and 41b so that all parts of the working plate means 2 describe circular paths which are the same as the circles along which the outer crank pins 41a and 41b turn, these crank pins of course turning around the axes of the crank discs 42a and 42b. Thus, the working plate means 2 interconnects the pair of crank means in much the same way that a pair of wheels of a locomotive are interconnected by a connecting rod which is pivotally connected at its ends to such a pair of wheels with these ends of the connecting rod going around the axes of the pair of wheels while the connecting rod itself moves around and around these axes. A substantially similar connection of the working plate means 2 to the pair of crank means 4a and 4b is provided with the structure of the invention. 60

It will be seen that the balancing plate means 3 is connected by way of the crank pins 43a and 43b to the pair of crank means 4a and 4b so that each part of the balancing plate means 3 will move along a circular path during rotation of the pair of crank pins 43a and 43b, and these circular paths of every part of the balancing plate means 3 will correspond to the circles along which the crank pins 43a and 43b turn respectively around the pair of axes of the pair of crank means 4a and 4b. Thus, the balancing plate means 3 is connected to the pair of crank means in a manner similar to the working plate means 2. Because the pair of second crank pins 43a and 43b which are connected to the balancing plate means are displaced by 180° respectively around the axes of the pair of crank 70

means 4a and 4b from the common axes of the outer or first crank pins 41a and 41b, the balancing plate means 3 is capable of eliminating any free inertia forces which of course would be highly undesirable. The weight of the working plate means 2 together with the four outer crank pins 41a and 41b, on the one hand, as well as the weight of the balancing plate means 3 together with the crank pins 43a and 43b, on the other hand, have together with the radii r^2 and r^3 with respect to each other such a relationship that the single center of gravity of the pair of weights or plate means 2 and 3 does not change its position during operation of the device with respect to the entire device of the invention. As is apparent from the drawing, the bodies 2 and 3 are shaped in such a way that they can have unobstructed movement relative to the support means 1. During use of the apparatus the movement of the bodies 1 and 2 with respect to each other is relatively small so that sealing of the bodies 1 and 2 relative to each other so as to prevent dust or dirt from entering into the structure of the invention, by the use of suitable rubber rings, sealing sleeves, or the like, is easily possible.

Assuming, for example, that the structure of the invention is working on a mass 14 which is substantially inelastic and can be compacted only to a small extent, then in such a case the speed of rotation of the crank means and the radius of the crank pins have with respect to each other such relationship that the height to which the device jumps from the mass 14 is so great that the time required for one revolution of each crank means is the time required for the center of gravity of the entire device to rise up and fall back down to its initial position. The size of the radius r^2 of each crank means and the speed of rotation thereof are chosen in such a way that the device jumps up away from the mass 14 and again contacts the mass 14 after falling down when the outer crank pins 41a and 41b have angular positions α in advance of their bottom dead center positions, as indicated in FIG. 3. Thus, the working plate means 2 will engage the mass 14 when the outer crank pins are in advance of their bottom dead center positions by an angle of less than 90° , and as a result of this operation there is provided a horizontal component W_h for the device and a predetermined vertical component W_v . The size of the radius r^2 and the speed of rotation n of the crank means will determine the magnitude of the vector W_u shown in FIG. 3, and thus the vertical component W_v will be equal to $W_u \sin \alpha$ while the horizontal component W_h will be equal to $W_u \cos \alpha$, as is apparent from FIG. 3.

During operation of the device the magnitude of the angle α automatically adjusts itself according to the yieldability of the mass 14 which is worked on, and when a change in the yieldability of this mass 14 is encountered the angle α will change until equilibrium is reached during which the angle α will remain the same throughout the operation until the nature of the mass 14 again changes. Assuming, for example, that the structure operates with a predetermined angle α and that the mass 14 changes in such a way that it becomes softer or more yieldable. As a result the extent to which the device jumps up from the mass 14 diminishes because the working plate means 2 will press further into the more yieldable mass when engaging the latter. As a result the time required for the jumping up and falling back of the device becomes smaller with the result that the angle α by which the crank pins 41a and 41b are in advance of their bottom dead center positions when the plate 2 encounters the mass becomes greater. This increase in the magnitude of the angle α , however, brings with it an increase in the magnitude of the vertical component W_v , so that as a result the extent to which the device jumps upwardly away from the mass increases. On the other hand, when the device encounters a harder, less yieldable mass, then the angle α will also change and will remain constant at the changed value.

During a reduction in the size of the angle α from 45° to 10° the magnitude of the vertical component W_v will drop to one quarter of the value which it has at an angle of α which is 45° , and the vertical component disappears or becomes zero when the angle α is zero. As a result, the device of the invention can never jump so high from the mass on which it is working that the working plate means 2 does not again engage the mass 14 during each revolution.

10 It is of distinct advantage that with the structure of the invention the horizontal component and thus the speed with which the device travels under normal operating conditions on the mass in which it is working becomes greater as the magnitude of the angle α diminishes.

15 The reversible transmission 10 makes it possible to reverse the direction of rotation of the crank means so that the device can be moved forwardly or rearwardly.

A further advantage of the structure of the invention as compared to those structures which include rotary unbalanced weights is that the device of the invention advances along the mass which is being worked on with a uniform speed.

20 The upwardly or downwardly directed inclinations in the surface of roadways or the like which are worked on during road building operations, for example, have no appreciable influence on the speed of advance of the structure of the invention since this speed depends only on the speed of rotation of the crank means.

25 All operations depend only on the speed with which the crank means are rotated and the size of the radius r^2 . The springs 13 associated with the motor 8 serve only to provide the motor 8 with a shock-free mounting.

30 At relatively low speeds of rotation of the crank means, the extent to which the device of the invention jumps up from the mass on which it is working increases according to the square of $1/n$, wherein n is the speed of rotation of each crank means, as the speed of rotation of each crank means diminishes and as the crank radius r^2 increases, so that at relatively low speeds of operation, 35 which is to say speeds of rotation of each crank means, the vibrating device operates very effectively as a tamping device, and thus is highly suitable for the compacting of cohesive, non-particulate masses.

35 It will be understood that each of the elements described above, or two or more together, may also find a useful application in other types of vibrating devices from the types described above.

40 While the invention has been illustrated and described as embodied in vibrating and tamping devices, it is not intended to be limited to the details shown, since various modifications and structural changes may be made without departing in any way from the spirit of the present invention.

45 Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

50 What is claimed as new and desired to be secured by Letters Patent is:

55 1. In a vibrating and tamping device for compacting a mass located beneath the device, in combination, first support means; a pair of rotary crank means, each of said rotary crank means including means for supporting the respective crank means on said first support means; for rotation about a predetermined axis of rotation and first and second crank pins angularly displaced from each other by 180° about said axis of rotation and the axes of said first and second crank pins being respectively parallel to said axis of rotation, said pair of rotary crank means 60 having at any given instant the same angular positions

relative to said support means, during operation of the device, so that at any given instant the angular position of said first crank pins with reference to the axes of rotation of the pair of crank means are identical and said second crank pins of said pair of crank means also have respectively with respect to said axes of rotation identical angular positions displaced by 180° about said axes of rotation with respect to the positions of said first crank pins; working plate means operatively connected to said first crank pins for movement therewith and located at the lowest part of the device during operation thereof, said working plate means being the only part of the device which engages the mass which is worked on by the device and said first crank pins rotatably mounted in said working plate means which latter constitutes a second support means; and balancing plate means operatively connected to both said second crank pins for movement with the latter for counterbalancing the movement of said working plate means to eliminate inertia forces, said balancing plate means remaining at all times out of engagement with the mass which is worked on by the device.

2. In a device as recited in claim 1, said working plate means being in the form of an open-top container having a bottom, mass-engaging wall and a continuous side wall extending upwardly from the periphery of said bottom wall, said first support means being in the form of an elongated channel member having a top wall and a pair of side walls extending downwardly from said top wall into the interior of said working plate means, said side walls of said first support means supporting said pair of rotary crank means for rotation, and said balancing plate means being located between said side walls of said first support means as well as between said top wall of said first support means and said bottom wall of said working plate means.

3. In a device as recited in claim 2, transmission means extending between and operatively connected to said pair of crank means for maintaining the latter in synchronous rotation with respect to each other, said transmission means also being accommodated within the space between said side walls of said first support means.

4. In a device as recited in claim 1, said pair of crank means, said working plate means, and said balancing plate means having with respect to each other a relationship which provides these elements with a common center of gravity which remains stationary with respect to said first support means during operation of the device.

5. In a vibrating and tampering device for compacting a mass located beneath the device, in combination, first support means; a pair of rotary crank means, each of said rotary crank means including means for supporting the respective crank means on said first support means for rotation about a predetermined axis of rotation and first and second crank pins angularly displaced from each other by 180° about said axis of rotation and the axes of said first and second crank pins being respectively parallel to said axis of rotation, said pair of rotary crank means having at any given instant the same angular positions relative to said support means, during operation of the device, so that at any given instant the angular position of said first crank pins with reference to the axes of rotation of the pair of crank means are identical and said second crank pins of said pair of crank means also have respectively with respect to said axes identical angular positions displaced by 180° about said axes of rotation with respect to the positions of said first crank pins; working plate means operatively connected to said first crank pins for movement therewith and located at the lowest part of the device during operation thereof, said working plate means being the only part of the device which engages the mass which is worked on by the device, said working plate means having a continuous bottom plate portion which engages the mass which is worked on by the device and said first crank pins rotatably mounted in said working plate means which latter constitutes a second support means; and balancing plate means operatively con-

nected to both said second crank pins for movement with the latter for counterbalancing the movement of said working plate means to eliminate inertia forces, said balancing plate means remaining at all times out of engagement with the mass which is worked on by the device.

6. In a vibrating and tamping device for compacting a mass located beneath the device, in combination, first support means; a pair of rotary crank means, each of said rotary crank means including means for supporting the respective crank means on said first support means for rotation first about a predetermined axis of rotation and first and second crank pins angularly displaced from each other by 180° about said axis of rotation and the axes of said first and second crank pins being respectively parallel to said axis of rotation, said pair of rotary crank means having at any given instant the same angular positions relative to said support means, during operation of the device, so that at any given instant the angular position of said first crank pins with reference to the axes of rotation of the pair of crank means are identical and said second crank pins of said pair of crank means also have respectively with respect to said axes of rotation identical angular positions displaced by 180° about said axes of rotation with respect to the positions of said first crank pins; working plate means operatively connected to said first crank pins for movement therewith and located at the lowest part of the device during operation thereof, said working plate means being the only part of the device which engages the mass which is worked on by the device and said first crank pins rotatably mounted in said working plate means which latter constitutes a second support means; balancing plate means operatively connected to both said second crank pins for movement with the latter for counterbalancing the movement of said working plate means to eliminate inertia forces, said balancing plate means remaining at all times out of engagement with the mass which is worked on by the device; means rotating said pair of crank means at a speed within a given range of speeds which together with the radial distances of said first crank pins from said axes of rotation bring about engagement of said working plate means with the mass when said first crank pins are respectively at an angle of less than 90° in advance of their bottom dead center positions.

7. A vibrating and tamping device for compacting a mass located beneath the device, comprising, in combination, first support means; a pair of rotary crank means, each of said rotary crank means including means for supporting the respective crank means on said first support means for rotation about a predetermined axis of rotation and first and second crank pins angularly displaced from each other by 180° about said axis of rotation and the axes of said first and second crank pins being respectively parallel to said axis of rotation; means co-acting with said pair of crank means for maintaining them respectively at the same angular positions and for rotating them synchronously, so that at any given instant the angular position of said first crank pins with reference to the axes of rotation of the pair of crank means are identical and said second crank pins of said pair of crank means also respectively have at any given instant with respect to said axes of rotation identical angular positions displaced by 180° about said axes of rotation with respect to the positions of said first crank pins; working plate means operatively connected to said first crank pins for movement therewith and located at the lowest part of the device during operation thereof, said working plate means being the only part of the device which engages the mass which is worked on by the device and said first crank pins rotatably mounted in said working plate means which latter constitutes a second support means; and balancing plate means operatively connected to both said second crank pins for movement with the latter for counterbalancing the movement of said working plate means to eliminate inertia forces, said balancing plate means remaining

at all times out of engagement with the mass which is worked on by said working plate means.

8. A vibrating and tamping device for compacting a mass located beneath the device, comprising, in combination, first support means; a pair of rotary crank means, each of said rotary crank means including means for supporting the respective crank means on said first support means for rotation about a predetermined axis of rotation and first and second crank pins angularly displaced from each other by 180° about said axis of rotation and the axes of said first and second crank pins being respectively parallel to said axis of rotation; drive means carried by said support means and operatively connected to said pair of rotary crank means for rotating the latter while maintaining them respectively at the same angular positions relative to said support means, so that at any given instant the angular position of said first crank pins with reference to the axes of rotation of the pair of crank means are identical and said second crank pins of said pair of crank means also have with respect to said axes of rotation at any given instant identical angular positions respectively displaced by 180° about said axes of rotation with respect to the positions of said first crank pins; working plate means operatively connected to said first crank pins for movement therewith and located at the lowest part of the device during operation thereof, said working plate means being the only part of the device which engages the mass which is worked on by the device and said first crank pins rotatably mounted in said working plate means which latter constitutes a second support means; and balancing plate means operatively connected to both said second crank pins for movement with the latter for counterbalancing the movement of said working plate means to eliminate inertia forces, said balancing plate means remaining at all times out of engagement with the mass which is worked on by said working plate means.

9. In a vibrating and tamping device for compacting a mass located beneath the device, in combination, an elongated channel member having a top wall and a pair of parallel side walls extending downwardly from said top wall; a first pair of coaxial, identical crank discs supported for rotation by said pair of side walls; a first inner crank pin extending between said side walls and fixed to said first pair of crank discs, the axis of said first inner crank pin being located at a given radial distance from the common axis of said first crank discs; a second pair of rotary crank discs coaxial with each other and identical with said first pair of crank discs, said second pair of crank discs also being supported for rotation by said pair of side walls and having their common axis parallel to the common axis of said first pair of discs; a second inner crank pin extending between said side walls and fixed to said second inner pair of crank discs, the axis of said second crank pin being located from the common axis of said pair of second discs by the same distance that the axis of said first inner crank pin is located from the common

axis of said first pair of discs; a first pair of outer coaxial crank pins respectively fixed to said first pair of discs at outer faces thereof located at the exterior of said channel member, said first pair of outer crank pins having their common axis located at a given distance from the common axis of said first pair of discs and displaced by 180° from the axis of said first inner crank pin; a second pair of outer crank pins having a common axis and respectively fixedly carried by outer faces of said second pair of crank discs which are located at the exterior of said side walls of said channel member, the common axis of said second pair of outer crank pins being spaced from the common axis of said second pair of discs by the same distance that the common axis of said first pair of outer crank pins are located from the common axis of said first pair of discs, and the common axis of said second pair of outer crank pins also being displaced by 180° about the common axis of said second pair of discs from the axis of said second inner crank pin; an open-top working member having a bottom, mass-engaging wall and a continuous side wall extending upwardly from the periphery of said bottom wall and having a pair of opposed parallel portions respectively extending alongside of said pair of side walls of said channel member and between which said pair of side walls of said channel member are located, said side wall portions of said open-top member being respectively formed with openings receiving all of said outer crank pins whereby during rotation of said crank discs said open-top member will act on a mass therebeneath to vibrate and compact the mass with said bottom wall thereof; and a balancing member located between said side walls of said channel member and respectively formed with a pair of bores which respectively receive said first and second crank pins, said balancing member counterbalancing said open-top member to eliminate inertia forces while remaining at all times out of engagement with the mass which is engaged by said bottom wall.

10. In a device as recited in claim 9, drive means carried by said channel member and operatively connected to at least one of said crank discs for rotating the latter.

11. In a device as recited in claim 9, transmission means interconnecting the pair of rotary crank discs which are carried by one of said side walls for compelling said crank discs to rotate synchronously.
